FOOT-OPERATED VISE

George S. Greeott, Healdsburg, Calif.

Application September 14, 1948, Serial No. 49,194

5 Claims. (Cl. 81—21)

1

This invention relates to new and useful improvements in vices and clamps and has for its primary object to provide a simple and convenient vise operable by a foot pedal.

Another important object of this invention is to provide a foot actuated vise, which can be easily locked in a clamped position and released by the application of pressure from an operator's foot so that the operator's hands are free to perform various operations on the material held in the vise.

A meritorious feature of this invention resides in the provision of a frame adapted to be fastened to a vertical support, a fixed jaw carried by the frame and a movable jaw swivelly carried by a lever pivoted to the frame, means being provided responsive to foot actuation for locking the jaws in a clamping position and for releasing the jaws from the clamping position.

Another meritorious feature of this invention resides in the provision of a guide element fastened at one end to the frame and depending outwardly therefrom, a transverse locking element being carried by the lower end of the guide element and adapted to engage a rack bar or ratchet bar, pivotally carried by the lower end of the lever carrying the movable jaw, in order to lock the movable jaw in clamping position with the fixed jaw.

Another meritorious feature of this invention resides in the provision of a foot pedal integrally formed with the rack bar and pivoted to the lower end of the lever so as to enable a latching and unlatching pressure to be exerted on the free end of the rack bar to associate and disassociate the same with a locking member carried by the lower end of a guide element.

These and ancillary objects and other meritorious features are attained by this invention, a preferred embodiment of which is set forth in the following description and illustrated in the accompanying drawings, wherein:

Figure 1 is a side elevational view of a vise constructed in accordance with the principles of this invention;

Figure 2 is an end elevational view;

Figure 3 is a top plan view;

Figure 4 is a fragmentary sectional view taken on line 4—4, of Figure 2;

Figure 5 is an enlarged fragmentary elevational view as seen from line 5—5, of Figure 1;

Figure 6 is an enlarged fragmentary sectional view of the means carried by the lower end of the guide member for locking the ratchet bar in selected position dependent upon the desired position of the movable jaw carried by the upper end of the lever and is taken on the line 6—6 of Figure 3;

Figure 7 is a sectional view taken on line 7—7 of Figure 1;

Figure 8 is a view in perspective of a modified jaw face, and;

2

Figure 9 is a view in perspective of another modification of the jaw face.

Referring to the drawings, the numeral 10 designates a main frame which is adapted to be mounted on a vertical support, such as a wall or the like. The means preferred for mounting the main frame 10 at an angle to the vertical support and spaced outwardly therefrom are a pair of vertically spaced angle irons 14 and 16 which are bolted as at 18 to the support. Bolt assemblies 20 and 22 or other conventional fastening means are provided for securing the frame 10 to the lateral extension of the angle irons 14 and 16, as seen in Figures 1 and 2.

15 A fixed jaw 24 is secured to the upper end of the main frame 10 by means of an integral lug 26 which extends laterally from the jaw and is secured to the frame by means of a cotter pin 28.

20 A pair of parallel integrally formed and laterally extending wings 30 and 32 project forwardly from the lower end of the frame 10. An elongated flexible lever 34 is pivoted between the parallel wings 30 and 32 by means of a pair of apertured ears 36 and 38 and a transverse bolt 40, having a suitable locking nut 42 associated therewith. The parallel lateral ears 36 and 38 are formed on the flexible lever 34 adjacent its upper end so that the lever is pivoted adjacent its upper end with its major portion disposed below the pivot point.

25 A companion jaw for the jaw 24 is carried by the upper end of the lever 34 and comprises a movable jaw 44. The movable jaw 44 is swivelly secured to the upper end of the lever 34 by means of a pair of parallel shoulders 46 and 48 which laterally project in parallel fashion forwardly of the lever. The shoulders 46 and 48 are provided with opposed notches 50, within which is swivelly disposed a rod 52. The rod 52 is secured to the back portion of the movable jaw 44 and is swivelly retained in the notches 50 by means of a pair of cotter pins 54 and 56 inserted transversely at the front of the notches, as seen in Figure 3.

30 A guide member 58, consisting of a pair of parallel bars 60 and 62 extend downwardly and outwardly from the wings 30 and 32 of the frame, the ends of the bars being welded to the wings. A locking pin 64 is transversely disposed between the lower ends of the bars 60 and 62 to engage a rack bar or ratchet bar 66 pivotally carried by the lower end of the lever 34, by means of a stirrup 68 secured to the lower end of the lever and provided at its lower end with a transverse pin 70.

35 As seen in Figure 4, an angle iron 72 is disposed at its inner angular portion on the pin or rod 70 and is integrally formed with the straight end of the rack bar 66.

40 Thus, the angular section 74 of the angle iron defines a foot pedal, while the angular section 76 attached to the rack bar defines an actuating member for moving the opposite end of the rack bar upwardly and outwardly.

The operation of the device thus far described is as follows:

With reference to Figure 1, it is to be noted that the device is shown in a full line open position and in a phantom line closed position. Operatively speaking, pressure from an operator's foot is exerted on the angular section 74 of the angle iron 72, the pressure moving the lever 34 around its pivot point and moving the rack bar 66 upwardly and forwardly through the complementary bars 60 and 62 of the guide member 58. When the desired pressure is exerted on the fixed jaw by the movable jaw 44, the foot pressure is released, thereby causing the nearest tooth on the rack bar 66 to engage on the locking pin 64 and lock the movable jaw to the fixed jaw, with the work clamped therebetween. To release the tooth of the rack bar from the locking pin, pressure is exerted on the section 74 of the angle iron, thereby disengaging the teeth and holding the teeth of the rack bar upwardly and out of possible engagement with the pin 64. In order to prevent the rack bar from moving outwardly of the guide member, a transverse stop pin 88 is secured between the bars 60 and 62 and spaced upwardly from the locking pin 64.

Aiding in the release of the jaws is a spring 82 which is anchored to a transverse slat 84 formed between the bars 60 and 62 and is anchored to the flexible lever 34, as seen in Figure 1. To stop the movable jaw at the widest desired opening, there is provided a transverse pin or rod 85, the same being secured between the wings 36 and 32, as seen in Figure 1.

The jaws per se may be formed of any suitable material and may be lined with wood or the like for use in cabinet wood work.

An alternative form of jaw structure is shown in Figures 8 and 9, either of these structures being adapted for use as the fixed or movable jaw. In this respect, a block 90 may be formed with a concaved face 92, the same being suitable for round work pieces such as pipes or the like.

As seen in Figure 9, a block 90 may be provided with a convex face 92 having a series of vertical slots or channels 94 formed in the face thereof, the channels being of various size to accommodate various round stock.

From the foregoing, it will be apparent that the device is adaptable for use in welding, wood-working and the like and will reduce the time needed for performing any desired operation, inasmuch as the vise will be controlled by foot pressure thus allowing the operator to employ his hands for setting the materials to be welded or glued, etc.

However, it is to be understood that while only one embodiment of this invention has been presented, various embodiments and changes in the details of construction may be effected without departing from the scope of the appended claims.

Having described the invention, what is claimed as new is:

1. A vise comprising a frame adapted to be secured to a vertical support, a fixed jaw carried by said frame, an extension laterally projecting from said frame, a flexible lever pivoted adjacent its upper end to said extension, a movable jaw carried by the upper end of said lever and cooperating with the fixed jaw upon swinging movement of the lever to clampingly hold a work piece, a guide member secured at one end to said extension and extending outwardly therefrom, a latching member transversely disposed at the

lower end of the guide member, a latching bar pivotally carried by said lever and engageable with said latching member for locking the lower end of the lever to the guide member in a selected position, means for moving said latching bar out of locking engagement with said latching member, and resilient means positioned between the lever and guide member for normally urging the upper portion of the lever outwardly so as to maintain the movable jaw in its non-clamping position.

2. A vise comprising a frame, means for attaching said frame to a vertical support, a fixed jaw carried by said frame, an extension laterally projecting from said frame, a flexible elongated lever pivoted adjacent its upper end to said extension, a movable jaw swivelly carried by the upper end of the lever, a guide member secured at one end to said extension and depending outwardly therefrom, a latching pin carried transversely by the lower end of the guide member, rack bar means carried by the lower end of the lever for engaging said pin and latching the lower end of the lever in a selected position with respect to the lower end of the guide member, foot pedal means connected to said rack bar means for effecting pivoting movement of the rack bar means and disengagement from said pin, and resilient means positioned between the lever and said guide member for normally urging the upper portion of the lever outwardly.

3. A vise comprising a frame adapted for attachment to a vertical support, a fixed jaw carried by the upper end of the frame, parallel wings projecting laterally from the lower end of the frame, an elongated flexible lever pivoted adjacent its upper end between the wings, a movable jaw swivelly carried by the upper end of the lever, a guide member integrally depending outwardly from the wings, the lower end of said lever being swingable toward the lower end of said guide member by pressure of an operator's foot, and complementary means carried by the lower ends of the lever and guide member for securing the lower end of the lever to the lower end of the guide member at a selected distance apart to clamp a work piece between the jaws under a selective pressure.

4. The combination of claim 3, wherein said last named means includes a transverse pin on said guide member, a rack bar pivoted at one end to said lever and having its opposite end slidably disposed through the guide member and adapted for engagement on the pin.

5. The combination of claim 4, wherein said rack bar is formed integral with an angular foot pedal, a pivot pin transversely disposed in the lower end of the lever, said foot pedal being seated on said pin and movable to disengage the rack bar from the pin.

GEORGE S. GREEOTT.
